(57) **CLAIM**

The ornamental design for a U-turn acoustic separation device, as shown and described.

DESCRIPTION

FIG. 1 is a front right perspective view.

FIG. 2 is a front view.

FIG. 3 is a left side view.

FIG. 4 is a right side view.

FIG. 5 is a rear view.

FIG. 6 is a top view; and,

FIG. 7 is a bottom view.

The broken lines of FIGS. 1-9 illustrate portions of the article and form no part of the claimed design.
